CLAIM

The ornamental design for the gas regulator, as shown and described.

DESCRIPTION

FIG. 1 is an overhead plan view of a gas regulator embodying my design;

FIG. 2 is a side elevational view thereof;

FIG. 3 is a bottom plan view thereof;

FIG. 4 is a front elevational view thereof;

FIG. 5 is a rear elevational view thereof; and

FIG. 6 is an overhead plan view similar to FIG. 1 but showing a first alternative embodiment thereof;

FIG. 7 is a side elevational view thereof;

FIG. 8 is a bottom plan view thereof;

FIG. 9 is a front elevational view thereof; and,

FIG. 10 is a rear elevational view thereof.

The side elevational view of each respective embodiment which is not shown in the drawings is a mirror image of the side view thereof which is shown.
